United States Patent Office

Des. 221,556
Patented Aug. 24, 1971

221,556

RELIGIOUS ORNAMENT

Elizabeth Wallace, 64 Clinton St.,
Paterson, N.J. 07522

Filed June 30, 1970, Ser. No. 23,758

Term of patent 14 years

Int. Cl. D11—02

U.S. Cl. D29—23

FIG. 1

FIG. 2

FIG. 1 is a front elevational view of a religious ornament showing my new design, the side opposite being identical thereto; and

FIG. 2 is a top plan view thereof.

I claim:

The ornamental design for a religious ornament, as shown and described.
